United States Patent [19]
Falini

[11] Patent Number: Des. 321,404
[45] Date of Patent: ** Nov. 5, 1991

[54] LIGHT BULB

[75] Inventor: Jesse R. Falini, West Chester, Pa.

[73] Assignee: Falburg Films Corporation, West Chester, Pa.

[**] Term: 14 Years

[21] Appl. No.: 501,629

[22] Filed: Mar. 29, 1990

[52] U.S. Cl. D26/2

[58] Field of Search D26/2, 3; 313/315, 317, 313/110, 112, 113, 116, 493, 634; 315/56, 57, 58

[57] CLAIM

The ornamental design for a light bulb, as shown and described.

DESCRIPTION

FIG. 1 is a side elevational view of a light bulb showing my new design, all sides being identical;
FIG. 2 is a top plan view thereof;
FIG. 3 is a bottom plan view thereof;
FIG. 4 is a side elevational view of a second embodiment of my new design, all sides being identical;
FIG. 5 is a top plan view thereof;
FIG. 6 is a bottom plan view thereof;
FIG. 7 is a side elevational view of a third embodiment of my new design, all sides being identical;
FIG. 8 is a top plan view thereof;
FIG. 9 is a bottom plan view thereof.

FIG. 1

FIG. 2

FIG. 3

FIG. 4

FIG. 5

FIG. 6

FIG. 7

FIG. 8

FIG. 9
